CLAIM

We claim the ornamental design for a tabletop master control, as shown and described.

DESCRIPTION

FIG. 1 is a perspective view of a tabletop master control according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a tabletop master control according to a second embodiment of our new design.

FIG. 8 is a front view thereof; and,

FIG. 9 is a bottom view thereof, the left side, right side, and top views, respectively, of the second embodiment being identical to the left side, right side, and top views of the first embodiment.

The rear views form no part of the design and are omitted.
